UNITED STATES PATENT OFFICE.

GEORGE B. MYERS, OF DENVER, COLORADO.

INTERNAL-COMBUSTION ENGINE.

Application filed January 26, 1927. Serial No. 163,668.

This invention relates to improvements in the construction of internal combustion engines of the type employed in connection with automobiles.

5 It is obvious that the ideal motor is one that will deliver a uniform torque to the drive shaft. This is only attained, however, in electric motors and turbines of various kinds.

10 In motors and engines that employ reciprocating pistons which are attached to crank pins by means of connecting rods, the rotative effect on the crank shaft is very irregular due to several causes, such as the variations

15 in the pressure on the piston at different parts of the stroke; the weights and the velocities of the reciprocating parts which absorb a large amount of the power during the period of acceleration and redelivers it

20 as they are brought to rest and the variations in the torque due to the angular position of the connecting rods. It is well understood that every reciprocating engine employing a crank shaft to the crank pin of which the

25 piston is connected by means of a connecting rod, has two points, known as dead center positions, in which no tangential component is present. These points are found at the extreme ends of the stroke. When the crank

30 pin occupies positions ninety degrees removed from the dead center positions, a given force acting on the piston will give the maximum tangential pressure on the crank pin. This is strictly true only if we

35 consider that the connecting rod is of infinite length and for connecting rods of ordinary length the maximum tangential pressure is obtained at positions that vary from the ninety degree position. The above general

40 remarks are intended merely to more clearly bring out the advantages of applicant's construction and are not intended for a complete explanation of the problem of twisting movement on crank shafts of reciprocating engines.

45 The ordinary four-cylinder, four-cycle internal combustion engine delivers only two power impulses to the crank shaft during each revolution and therefore requires the use of a heavy fly wheel to smoothen out the irregular torque effort.

50 It is the object of this invention to produce an internal combustion engine in which the usual cranks and connecting rods are dispensed with and in which the power generated by the reciprocating pistons is transmitted to the drive shaft and converted into

rotary motion, in one direction, by means of a rack and pinion mechanism in which the pinion is mounted on the drive shaft and connected with it by means of a ratchet mechanism that permits the pinion and shaft to have relative rotation in one direction, but not in the other. When the pistons move in one direction, by power derived from the explosive charge, they will rotate the shaft and reciprocate the other pistons during the exhaust, intake and the compression strokes. In this way, the force exerted by the expanding gases will be converted into a twisting moment which is directly proportional to the force at every position of the piston. By this construction a more uniform torque is obtained than when a crank shaft and connecting rods are used.

55 This invention can be most clearly described and will be most readily understood when reference is had to the accompanying drawings in which the preferred embodiment of the invention has been illustrated and in which:

Fig. 1 is a front elevation of the engine showing the same in assembled condition;

Fig. 2 is a side elevation of the engine, a portion of the side wall being broken away to more clearly disclose the construction;

Fig. 3 is a transverse section taken on line 3—3, Fig. 2;

Fig. 4 is a view taken along plane 4—4, Fig. 3, and shows a portion of the mechanism; and

Fig. 5 is a section taken on line 5—5, Fig. 4.

My improved engine consists of a cylinder block 1 having sides 2 which extend downwardly from each side and end thereof, and which are provided with outwardly extending flanges 3. A pan 4 is also provided with a flange 5 which is adapted to fit against the outer surface of flange 3 and is secured to the latter by bolts 6. When the pan 4 is in place, it cooperates with the walls 2 to form a chamber through which the main shaft 7 extends and which contains the greater number of the movable parts. The cylinder block is provided with eight cylindrical chambers 8, four of which are located on each side of a vertical plane passing through the axis of the shaft 7 (Fig. 3). The cylindrical chambers on each side are identical in size with the corresponding cylindrical openings on the other side and form four pairs of parallel cylinders in which the

cylinders of each pair are in axial alignment. The walls 9 of the cylinders are partially surrounded by a water packet 10 through which the cooling water is circulated, the 5 group of cylinders on each side having a separate distinct water jacket from the group on the other side. Cored cylinder heads 11 are secured to the sides of the cylinder block by means of bolts 12. Openings 10 13 in the cylinder block connect the water jacket spaces 10 with the water jacket spaces 14 in the cylinder heads 11. Each cylinder has slidably mounted therein a piston 15, whose outer surface is provided with annular 15 grooves for the reception of the piston rings 16 and may also be provided with a spiral groove 17, which serves to distribute the oil for lubrication. The pistons of each pair of aligned cylinders are rigidly connected by a bar 18 and therefore reciprocate 20 as a unit. In the engine, as illustrated, there are four of these piston units and there may be six or any other even number of duplex piston units, as the engine is made up of several 25 identical groups, each of which has four cylinders forming two pairs of aligned cylinders. In the engine illustrated, there are two such groups which is the equivalent of an eight-cylinder engine. As the mechanism 30 and parts of each group are identical, one group only will be described. The inner surface of each cylinder head is provided at the end of each cylinder with a depression 19 into which the heads of the poppet valves 35 20 extend, one intake and one exhaust valve being provided for each cylinder. The valves shown in Fig. 3 are exhaust valves and serve to connect the interior of the cylinders with the interior of the exhaust manifold 21. Valve springs 22 serve to hold the 40 valves in closed position. The valves are opened at certain times in each cycle by the cams 23 which engage valve tappets 24. The cam shafts are rotated from the drive shaft 45 7 by means of suitable gears and the cams open and close the valves in regular sequence. As the valve mechanism is identical with that employed in internal combustion engines of ordinary construction and only 50 such changes have been made as will adapt them to this particular construction, no further detailed description will be given. The four cylinders and pistons of each group correspond to the four cylinders and pistons of the ordinary four-cycle, four cylinder engine and charge, compress, fire and exhaust in a predetermined order. The shaft 7 takes the place of the crank shaft of the ordinary engine and has been shown as 55 60 journaled in three spaced bearings 25, 26 and 27, bearing 26, being the center bearing. Secured to shaft 7 are two ratchet members, one of which is shown in section in Figs. 2 and 3, the other being located on the other 65 side of the hub 29 of the cam member.

These ratchet members are held against rotation by means of keys 30 and are each provided with several cut-outs 31, whose bottoms are flat and are formed by portions of chord planes. These cut outs are unsymmetrical with respect to a radial plane bisecting the chord that corresponds in position with the plane of the bottoms and have the greater portions lying to the same side of this perpendicular bisector. In the illustration given, the cut outs have their major portions extending in a clockwise direction from the center point of the chord. The flat-bottoms 32 of the cut outs terminate in end-walls 33 and 34 that are substantially radial. Within each cut out are two cylindrical steel rollers 35. The ends of the cam members 28 are reduced in diameter so as to form cylindrical extensions 36, to which are secured the ball bearings 37. Enclosing each ratchet member 28 are two gears 38. These gears are identical in size and shape and are provided on their adjacent surfaces with a circular recess whose depth is equal to one-half of the width of the ratchet member 28 and whose diameters are equal to the outside diameter of the same ratchet member. When the gears are in place, they form an enclosing housing for the ratchet member and are rotatable with respect to it. The ends of hub 29 and ends of the bearings 25 and 26 hold the gears 38 against longitudinal movement. It is apparent that the gears 38 can rotate about the ratchet member 28 in a counter clockwise direction (Fig. 100 3), but not in the opposite direction for as soon as an attempt is made to rotate the gears in a clockwise direction, one or more of the rollers 35 will roll along planes 32 and outwardly towards the interior wall of 105 the recess in the gear wheel and therefore, when the gears are turned in a clockwise direction they will rotate the shaft 7.

Secured to the flattened central part of the bar 18 of each piston unit is a yoke member 110 comprising an arm 39 whose upper end is flanged and provided with openings for the reception of the bolts 40. These arms are integral with the upper rack bar 41 of the yoke. This bar is provided on its lower surface with gear teeth 42, which are adapted to engage the teeth of and cooperate with one of the gear wheels 38. The opposite ends of bar 41 are joined to the corresponding ends of the rack bar 43 by means of connecting members 44 and 45. Rack bar 43 is not located in the same vertical plane as bar 41, but is offset and engages the lower side of the other gear 38 of the same pair.

It will now be evident that when the pistons 15 move axially, they carry with them the arm 39 and rack bars 41 and 43 and thereby rotate the gears 38. Since rack bar 41 engages the upper side of one of the gears 38 and rack bar 43 the under side of 130

the other gear of this pair, these gears will rotate in opposite directions and consequently one of them will always rotate clockwise and will therefore impart a corresponding rotation to shaft 7.

Secured to the other pair of pistons is another yoke piece that is a duplicate of the one described and whose rack bars 41 and 43 cooperate with the other pair of gears 38. The ends of these two yoke members are connected by means of bolts and form in effect a rigid unitary structure having two arms 39 and four rack bars which engage the four gears 38. A steel plate 47 is secured underneath the cylinder block on each side of the longitudinal central plane and a corresponding plate 48 is secured to the upper surface of the ends of the yoke members. Plates 47 and 48 form guides that resist the forces which tend to distort the arms 39 when the engine is producing power.

From the above description it is evident that if the cams 23 are so adjusted and so connected to the drive shaft that the four cylinders of the group will charge, compress, fire and exhaust in a regular predetermined sequence analogous to that of any other four cycle engine, the order of firing alternating from one side of the central longitudinal plane to the other that shaft 7 will be rotated in a clockwise direction (Fig. 3).

In engines having cranks and connecting rods, the length of the stroke is positively determined by the diameter of the circle traveled by the crank pin. The apparatus as far as it has been described has nothing to determine the length of the stroke, which, however, is essential. Means have, however, been provided for this purpose and this will now be described in detail.

Referring now more particularly to Figs. 4 and 5 where the yokes and associated parts have been shown apart from the engine structure, it will be observed that the hub 29 carries three cam members 49, each of which has a tip or point 50 and which are symmetrical with respect to a line joining the tip with the center line of shaft 7. Clamped in place between the end members 44 and 45 are socket members 51, which are provided with a noncircular opening 52 and a smaller axial circular opening 53. A plunger 54 has two parallel arms 55 between which is journaled a roller 56. The plunger 54 has a cylindrical extension 57 that extends out through the opening 53. A coiled spring 58 is under compression and tends to move the roller inwardly against the cam faces. The cams are secured to the shaft and are so positioned that at the end of each stroke they occupy a position like that shown in Fig. 5 which represents the extreme right hand position of the yokes and

the pistons to which they are attached. When the parts have reached the piston shown in Fig. 3, the charge in one of the cylinders on the righthand side is ignited and the yoke members begin moving towards the left. If there should be a premature ignition of the charge, the roller 55 would not yet have reached the point of the cam and therefore any movement towards the left would be prevented for the reason that the shaft 7 can rotate only in one direction. The yokes can, therefore, not reverse their direction of travel until the parts have assumed a position substantially like that shown in Fig. 5. Since there are three cam members 49, one stroke must rotate the shaft one-sixth of a revolution. The springs 58 serve to hold the rollers against the surfaces of the cams at all times and therefore prevent noise.

The movable parts are lubricated by means of a forced lubricating system comprising an oil pump 59 which is rotated from the main shaft through the medium of a train of gears in the manner indicated by dotted lines in Figure 1. A pipe 60 extends from the intake port of the oil pump and into the interior of the pan 4 where another pipe 61 connects it with the strainer 62. Oil may be stored in the pan 4 to any depth desired. When the pump is in operation, the oil is carried upwardly through pipe 60 and delivered to the oil pump. From the delivery port of the oil pump, pipes 63 and 64 extend to the top of the engine where they connect with the branched nozzles 65 (Fig. 3), from which the oil emerges in a spray directly over each of the valves, there being a nozzle 65 for every inlet and outlet valve. Each cylinder wall is provided with two openings 66 through which the oil may flow to the interior of the cylinder. As the pistons reciprocate, oil is caught in the helical groove 17 and distributed evenly over the cylinder surface. The excess of oil flows downwardly over the gears and cams and is finally deposited in the bottom of pan 4, where it is ready to begin another cycle. The main bearings are lubricated by oil provided through pump 59. Pipe 67 extends from the delivery port of the pump to a branched coupling 68, from which pipes extend to the main bearings. In Figure 2, two of these pipes have been shown and have been numbered respectively, 69 and 70. From Figure 2 it will be apparent that the oil that is forced into the main shaft bearings will divide and part will flow inwardly to the ratchet members 28, thereby producing a thorough and reliable lubrication of all the moving surfaces.

For the purpose of circulating the cooling water, I have provided a water pump 71 that is connected to the lower end of an or-

dinary automobile radiator by means of tubes 72. The water is delivered to the water jacket spaces in the engine block and finally emerges through the tubes 73 from 5 which it returns to the radiator. The exhaust ports have been designated by numeral 21 and extend to a suitable exhaust pipe not shown. The intake ports are connected by means of a manifold 74 and pipes 75 with 10 an ordinary carburetor which has been indicated by numeral 76. As there is nothing new about the carburetor or the manifolds, these will not be described in detail.

For the purpose of providing ignition current I have shown the engine equipped with 15 a standard ignition device and distributor. The magneto being designated by numeral 77, while the distributor is designated by numeral 78. From the distributor high tension wires 79 extend to the various spark plugs 80, and as the engine operates high tension current is directed in a predetermined sequence to the various cylinders. As indicated above, the ignition system is 20 merely an adaptation of an old and well known system used extensively for this purpose and has merely been shown for the purpose of more clearly illustrating the construction and operation of the engine.

30 In Figure 1 I have also shown the ventilating fan, which has been designated as a whole by numeral 81.

From the above description it would be apparent that I have made a radical departure in the construction of internal combustion engines. The distinguishing feature of this engine is that I have dispensed with the cranks and connecting rods that are employed almost universally in engines of this 35 type, and have substituted for these a mechanism by means of which the reciprocating motion of the piston is converted into rotary motion in one direction. I have also provided my engine with means for positively determining the length of the stroke 40 and for preventing a reverse movement of the pistons before the end of the stroke is reached. With my improved engine, there is no danger of backfiring, as the crank shaft 45 can rotate in one direction only, and if a force is applied which tends to rotate the shaft in the opposite direction, this will be resisted by the action of the cams 49 and the rollers 56.

55 As intimated above, this engine comprises one or more groups of duplicate parts, each of which groups is complete in itself and forms a four-cycle, four cylinder engine. These groups can be assembled so as to operate on the same shaft and an engine can 60 therefore be readily built which corresponds to a four-cycle engine having any number of groups or units.

Having described the invention what is 65 claimed as new is:

1. An internal combustion engine comprising a cylinder block having a plurality of pairs of longitudinally spaced axially aligned cylinders, a piston slidably mounted in each cylinder, means for rigidly connecting the pistons whereby they will reciprocate as a unit, a shaft having its axis in a plane parallel with a plane containing the axes of the pistons, the axis of the shaft extending in a line perpendicular to the direction of the axes of the pistons, means for connecting the pistons to the shaft, said means comprising a pair of gear wheels each of said wheels being adapted to be intermittently secured to the shaft, a ratchet mechanism 70 interposed between each gear and the shaft for preventing relative rotation of the shaft and the gears in one direction while permitting relative rotation in the other direction, two racks carried by each group of interconnected pistons, said racks enclosing the shaft and each rack engaging a different gear wheel whereby the shaft will be rotated in the same direction whenever the pistons reciprocate and means for preventing the pistons from reversing the direction of travel before they have reached the end of the stroke, said last named means comprising a cam member carried by the shaft and cam engaging rollers carried by the rack 75 members.

2. An internal combustion engine comprising, in combination, an engine block having four cylinders forming two pairs, the cylinders of each pair being longitudinally spaced and axially aligned, a pair of opposed rigidly connected pistons slidably associated with each pair of cylinders, means for interconnecting the pistons so as to form a group, a shaft mounted for rotation in a plane spaced from and parallel to the common plane of the axes of the pistons and about an axis perpendicular to the direction of reciprocation of the pistons, two spaced parallel racks connected with each pair of aligned pistons, one rack of each pair being located on each side of the shaft, two pairs of gear wheels, each of said wheels being adapted to be intermittently secured to the shaft by means of a ratchet mechanism, one rack of each pair cooperating with one gear of each pair whereby the gears of each pair will be rotated in opposite directions whenever the pistons reciprocate and means for preventing the pistons from reversing their direction of movement before 100 the end of the stroke has been reached.

3. An internal combustion engine comprising, in combination, an engine block having four cylinders forming two parallel pairs, the cylinders of each pair being longitudinally spaced and axially aligned, a pair of opposed rigidly connected pistons slidably associated with each pair of cylinders, a shaft mounted for rotation in a plane parallel to the common plane of the axes of the pistons 105 110 115 120 125 130

- and about an axis perpendicular to the direction of reciprocation of the pistons, two spaced parallel racks connected with each pair of aligned pistons, means for rigidly 5 interconnecting the two pairs of racks, the racks of each pair being located on opposite sides of the shaft, two pairs of gear wheels secured to the shaft by means of a ratchet mechanism, one rack of each pair cooperating 10 with one gear of each pair, whereby the gears of each pair will be rotated in opposite directions whenever the pistons reciprocate and means for preventing the pistons from reversing their direction of movement 15 before the end of the stroke has been reached, said last named means comprising a cam rigidly secured to the shaft and rollers carried by the rack members.
4. An internal combustion engine comprising, in combination, four pistons forming two pairs, each pair consisting of two axially aligned pistons arranged in opposed relation, the pistons of each pair being parallel, means for interconnecting the two 25 pairs so as to form a group that moves as a unit, a shaft located to one side of said pistons, means for supporting the shaft so that it may rotate about an axis perpendicular to the axes of the pistons and which lies in a plane spaced from and parallel with a plane that contains the axes of the pistons, a cylinder block having cylindrical openings in which the pistons may reciprocate in the 30 direction of their axes, means for converting the reciprocating motion of the pistons into a rotary motion of the shaft, said means comprising a ratchet mechanism that permits each wheel to rotate freely about the 35 shaft in one direction but which prevents it from rotating relative to the shaft in the opposite direction, two racks carried by the piston group, said racks enclosing the shaft, one rack engaging each gear wheel whereby, 40 when the pistons are reciprocated the shaft will be rotated, means comprising cams carried by the shaft for determining the length of the stroke of the pistons and for preventing the pistons from reversing their direction of travel before the stroke has been completed 45 said means comprising a cam carried by the shaft and cooperating cam engaging means carried by the racks.

In testimony whereof I affix my signature.
GEORGE B. MYERS.
